UNITED STATES PATENT OFFICE.

LEWIS S. CHILSON, OF ATTLEBORO, MASSACHUSETTS, ASSIGNOR TO J. M. FISHER COMPANY, OF ATTLEBORO, MASSACHUSETTS, A CORPORATION OF RHODE ISLAND.

BELT BUCKLE.

Application filed March 2, 1925. Serial No. 12,564.

This invention relates to that class of buckles which are provided with a clamping member adapted to engage and bind belts of different thicknesses against the buckle body; and the object of this invention is to provide a clamping member for the buckle in which a tension on the bail, causes it to exert a pressure on the clamp to grip the belt against the body of the buckle, to hold the belt in adjusted position about the body of the wearer.

A further object of this invention is the provision of a bail member having outturned end portions set at an angle to their axis of rotation thereby adapting these ends to exert a cam action upon the back of the clamp causing it to grip the belt against the buckle body when tension is applied to the bail by a strain on the belt.

With these and other objects in view, the invention consists of certain novel features of construction, as will be more fully described, and particularly pointed out in the appended claims.

In the accompanying drawings:

Figure 1 is a view of the inside of the buckle of my improved construction showing the bail as having outturned ends pivoted in the body and the clamping member as pivoted on the outturned ends of the bail.

Figure 2 is a perspective view showing the under side of the clamping member removed from the body of the buckle.

Figure 3 is an end view sectioned on line 3-3 of Figure 1, showing the clamping member as pivoted on the bail in the body of the buckle.

Figure 4 is a central edge view illustrating my improved form of clamp as being forced inwardly by tension on the bail to clamp the belt end against the body.

Figure 5 is an enlarged sectional elevation illustrating the clamp and the cam action of the bail as forcing the clamp inward to bind the belt against the buckle body.

Figure 6 is a fragmental view illustrating one of the outturned ends of the bail as set at an angle to its axis of rotation whereby the moving of the bail from raised position over to operating position where it is under tension by the belt end, which movement exerts a cam action upon the clamp to force the other end of the belt against the body of the buckle.

Figure 7 is an edge view of the bail illustrating the angularly-disposed offset or outturned end thereon.

It is found in the practical construction and operation of belt buckles of this character, of advantage to provide a buckle which is inexpensive in construction and one which is adapted to bind and firmly hold the belt against the body of the buckle, and to accomplish this in a simple and effective way, I have provided a bail with an outturned end portion set at an obtuse angle to their side arms of the bail and at an angle to their axis of rotation and have pivotally mounted these ends in the body of the buckle, and I have also provided a clamping member with a plurality of biting edges and pivotally mounted this clamping member upon the outturned angularly-disposed end portions of the bail, whereby a swinging movement of the bail from inoperative to operative position serves to carry the clamp inwardly and cause it to grip and bind the belt against the inner surface of the buckle body and the greater the tension upon the belt the greater is the binding action of the gripper to prevent the belt from slipping in the buckle; and the following is a detailed description of the present embodiment of my invention showing one means by which these advantageous results may be accomplished.

With reference to the drawings, 10 designates the body of a buckle which may be made in any desired form, the same being provided with rearwardly-turned side flanges 11, each having a pivot ear 12 thereon, pierced at 13. I have also provided a belt member 14 to which one end 15 of the belt is attached. This belt member is formed in any suitable way but I have herein shown the same as being formed of wire having oppositely outturned end portions 16 of a substantial length, the extremities of these end portions extending through the piercings 13 of the ears 12 and are headed over as at 17 on the outside thereof. These outturned end portions are set on an obtuse angle to the axis of the side arms 18 of the bail or at an angle to the axis of their rotation for the purpose presently described.

I have provided a gripping or clamping member 19 for binding the free end 20 of the belt against the inner surface of the body

of the buckle, to retain it in any desired position against the slipping strains applied to it by motions of the body of the wearer.

This clamping member is provided with 5 rearwardly extending side ears 21 pierced as at 22 with holes, preferably of a size larger than the diameter of the bail end which extends through it and these ears 21 are mounted on these outturned ends of the 10 bail member between the side arms of the bail and the pivot ears of the buckle body whereby a swinging movement of the bail having end portions set at an angle to their pivotal axis, are caused to exert pressure 15 upon the clamp 19 as the bail is swung from inoperative to operative position under tension of its end of the belt wherein a cam action is provided to exert an inward pressure to cause the gripping member to bind 20 the free end 20 of the belt against the inner side of the buckle body and the greater the tension on the belt the greater is the pressing action of these cam ends to force the gripper in and bind the belt against the 25 body.

The enlarged holes in the clamp ears serve to permit of its adjustment for belts of different thicknesses.

In some instances, I prefer to provide the 30 gripping member with a plurality of gripping edges and in some instances, I corrugate these gripping members to better grip the back of the belt and so effectually prevent slipping of the same.

My improved belt buckle is extremely 35 simple and inexpensive in construction and is effective in its operation and by its use belts of different thicknesses may be employed and securely held in the buckle body against slipping under excessive strains exerted by movement of the body of the wearer.

The foregoing description is directed 40 solely towards the construction illustrated, but I desire it to be understood that I reserve the privilege of resorting to all the

mechanical changes to which the device is susceptible, the invention being defined and limited only by the terms of the appended 50 claims.

I claim:

1. A buckle having a body portion, a clamping member having end ears, a bail member having outturned ends extending through said ears and pivoted in said body portion, said bail lying substantially in a single plane and being in proximity to the rear surface of said clamping member so as to exert a pressure thereon when under tension by the belt. 55

2. A buckle having a body portion, a clamping member, end ears thereon extending rearwardly therefrom, a bail member having legs with outturned ends extending through said ears at a point adjacent the 60 rear surface of the clamping member and pivoted in said body the legs of said bail member engaging the rear surface of said clamping member to force it to bind the belt against the body. 70

3. A buckle having a body portion, a bail member having outturned end portions pivoted in said body, said outturned portions being set at an angle to the axis on which they rotate, and a clamp member pivoted on said 75 angular bail ends whereby the bail is caused when under tension of the belt to exert a pressure on said clamping member to bind the belt against the body. 80

4. A buckle having a body with rearwardly extending portions, a clamping member mounted between said portions and having a plurality of clamping edges, a bail member having outturned end portions mounted in said body for rotation, said outturned portions being set at an angle to their axis of rotation and positioned in proximity to said clamp to exert pressure on the back of said clamp to bind the belt against the body. 85 90

In testimony whereof I affix my signature.

LEWIS S. CHILSON.
